UNITED STATES PATENT OFFICE.

JOSEPH F. PTACEK, OF MILWAUKEE, WISCONSIN.

RUG-WEAVING MACHINE.

Application filed May 20, 1926. Serial No. 110,371.

My invention relates to a manually operated loom designed for domestic use in the production of rugs and mats.

It comprises an aligned row of relatively fixed hooks positioned at one side of the loom and a companion aligned row of rotatable hooks arranged so as to oppose the first named row. An endless warp is extended between the hooks, engaging first a hook in one row and then the companion hook in the opposite row, then passing back to the second hook in the first row and then to the second hook in the second row, and so on until the warp has been extended between the hooks of both rows so as to provide a sheet of warps having the width of the rug or mat to be produced. The two opposed rows of hooks are properly spaced from each other so as to provide for the desired length in rug or mat.

The rotatable hooks are each provided with a pinion, the row of pinions on such hooks being in mesh with each other, so that all may rotate at the same moment, but the alternate hooks rotating in opposite directions.

Two certain of the rotating hooks are provided with sprocket wheels about which is passed an endless chain, the latter being connected at a point intermediate its ends in one of its runs with a vibrating hand lever, so that by this means a movement of rotation is imparted to the hooks of one row so as to displace alternate warps from their common plane into two substantially parallel planes, and so form a shed into which the weft is laid and beaten up. A reverse movement of the hand lever will shift the warps into opposite positions to form the next shed.

The relatively fixed hooks are carried upon a movable bar which is counter-weighted to position it for placing the warp upon the hooks of the two bars, and then moved by a treadle to place the warps under tension. As the weaving proceeds, the length of the warp is gradually lessened to the defined length of the rug or mat, and to compensate for this reduction in the length of the warps, the movable bar upon which the tension is exerted may be shifted successively to other positions and there held during the further weaving.

The constructional features of the inven-

tion will now be described in detail, and the novelty thereof pointed out in the appended claims.

In the accompanying drawings:

Fig. 1 is a view in front elevation of a loom constructed in accordance with my invention, and showing the warps in one of their shed-forming positions.

Fig. 2 is a plan view of the upper portion thereof.

Fig. 3 is a vertical sectional view from front to rear, looking from the left of Fig. 1.

Fig. 4 is a view in front elevation of the upper left hand side of the loom showing the position of the rotatable hooks at the time the warp is laid therein.

Fig. 5 is a similar view showing the hooks as having been partially rotated to form a shed, as in Fig. 1.

Fig. 6 is a similar view showing the hooks as having been rotated to the reverse shed-forming position.

In the drawings, the numerals 10 and 11 indicate the uprights of the frame of the loom, secured at their lower ends to rearwardly extending base members, one of which is indicated by the numeral 12, in Fig. 3. The uprights are tied together by fixed cross beams 13, 14 and 15, so as to form a rectangular frame of suitable height and width, and for the purpose of effecting stability in the structure, diagonal braces 16 and 17 may be extended between the upper ends of the uprights 10 and 11 and the rear ends of the base members 12, in the manner shown in Fig. 3.

The fixed cross beams 13 and 14 also function as supports for the upper hooks 18, and are provided with aligned vertical bores, in each two of which the shaft 19 of an upper hook 18 is journaled for rotation. Fixed at an intermediate point in the length of the shaft 19 is a collar 20, which, in the construction illustrated, is adapted to rest upon the upper side of the cross beam 14, and so serve to restrain the axial movement of the shaft 19 under the tension of the warp 21, when applied to the hooks, and to otherwise support the shaft and its hook in proper position. A pinion 22 is keyed or otherwise fixed upon the end of each shaft 19, projecting above the cross beam 13. A washer 23 may be interposed between the lower hub of the pinion 22 and the top of the cross

beam 13, so as to distribute the pressure which otherwise would be wholly upon the collar 20 of the shaft 19.

A lower, complementary, co-operating cross bar 24, carrying hooks 25 fixed therein, is arranged for vertical movement at the front of the loom. Each end of the cross bar 24 is perforated for the reception of a pin 26, 26', which latter is adapted to be entered in any one of a plurality of transverse bores 26" in spaced vertical order in the lower part of the uprights 10 and 11, so that the said cross bar 24 may be placed in any one of several positions. Rope sheaves 27 and 28, are journaled upon the inner sides of the uprights 10 and 11, respectively, at a suitable distance from the floor. Cords 29 and 30, attached in any convenient manner to the ends of the cross bar 24, pass over the rope sheaves, and are connected at their other ends to weights 31 and 32, the latter lifting the said cross bar 24 when freed for movement, and preserving its parallelism during such movement.

With the parts arranged as shown in Fig. 1, the cross bar is maintained in initial position by passing the pins 26, 26', into the opposite holes 26" in the uprights 10 and 11, that is, in the second or third holes in the order of their ascent. Commencing at the left of the lower cross bar 24 the end of the warp is secured to the first hook 25, and then passed over the first hook 18 at the left of the upper set, then returned under the second hook of the lower set, and then over the second hook of the upper set, and so on, until the warps are spread for the width desired, after which the last end of the warp will be attached to one of the hooks, as at the beginning. Any slack which exists in the sheet of warps, may be taken up by withdrawing the pins 26, 26', and lowering the cross bar 24 to stretch the warps. In order that this may be done with ease, I provide a treadle 33, pivoted at its rear end to the underside of the bottom cross beam 15 near the middle of the latter, and connected intermediate its ends to the cross bar 24, by a link or links 34. By depressing the treadle 33, the holes in the ends of the cross bar may be brought into register with lower holes in the uprights 10 and 11, and the cross bar be secured in its new position by the pins 26, 26', as before described.

In this connection, it will be in order to state that as the weaving proceeds the warps gradually become shortened, due to their deflection about the weft, as will be later described. To compensate for this condition, and when the tension upon the warps approaches a condition that requires their relaxation to permit the weaving to proceed, the treadle 33 will be depressed so as to permit the withdrawal of the pins 26, 26', thus freeing the cross bar 24 for upward

movement under restraint of the treadle 33 until the holes in the ends of the cross bar are brought into register with next pair of holes 26" above. The pins are then inserted in the registering holes to hold the cross bar 70 in fixed position during the next period of weaving. This operation of shifting the position of the cross bar 24 may be repeated as often as is necessary in the weaving operations.

As hereinbefore stated, a pinion 22 is fixed upon the upper end of each shaft 19, all of which shafts are aligned in the direction of the length of their supporting cross beams 13 and 14. The pinions 22 mesh one with 80 the next across the loom, so that all rotate together, the even numbered ones in one direction and the odd numbered ones in the opposite direction.

Two of the shafts 19, one near each opposite side of the loom, are extended upwardly for a short distance, and have fixed upon the extending ends sprocket wheels 35 and 36 about which is passed an endless chain 37. A bracket 38, extending rearwardly of the loom, is attached to the cross beams 13 and 14 at or near their middle. The said bracket is provided with a pivot 39 upon which is mounted for lateral vibration a hand operated lever 40, connected intermediate its 95 ends, by a pin 41 set therein to one of the runs of the chain 37. Stops 42 and 43 mounted upon the bracket 38, limit the vibrations of the hand lever 40, so that in the oscillations of the latter, the chain 37 is 100 moved to turn the sprockets and through them the row of pinions, together with the hooks 18 upon the lower ends of the shafts upon which the pinions 22 are mounted. The extreme throw of the hand lever 40 105 effects a rotation of the hooks through an arc of 180°, that is from one shed forming position shown in Fig. 5, through the intermediate position shown in Fig. 4, to the reverse shed forming position shown in Fig. 6. An 110 extreme throw of the hand lever 40 in either direction from its neutral position will turn the warps from their common plane as illustrated in Fig. 4, so that they will stand in parallel planes as shown in Figs. 5 and 115 6, so that a shed is formed into which a weft 44 may be laid and beaten up. In such movement of the hand lever, the alternate hooks 18 rotate together and oppositely to the others, as is shown in Figs. 1, 5 and 6. 120 After the weft 44 has been laid in the first shed and beaten up to the fell of the fabric, the hand lever 40 is given an opposite movement so as to cross the warps about the weft just laid and form a new shed into which the 125 weft may be laid after being turned about the outer warps so as to form a good selvage. The weft last laid is then beaten up, and the weaving continues, the weft being turned alternately about the selvage warps as the 130

sheds are successively formed. As the fabric being woven approaches completion, a point is reached at which insertion of the weft will be attended with some difficulty, but this may be facilitated at such time by the use of a long needle for inserting the weft in the last shed as the opposite fell of the fabric is reached.

Upon completion of the weaving, the cross bar 24 is released from its last fixed position and the tension upon the fabric is permitted to relax. The hand lever 40 is thrown to its neutral position, to face the hooks 18 to the front of the loom as shown in Fig. 4. The loops may be slipped off the hooks 18 and 25 of the rows, and the completed fabric removed from the loom. By slightly shaking or beating the fabric, the warps and weft threads will assume natural positions and the rug or mat will lie flat upon the floor.

Having thus described my invention, what I claim and desire to secure by Letters Patent of the United States, is:

1. In a rug weaving loom, a frame composed of two uprights connected at their upper ends by parallel cross beams each provided with a row of aligned holes, vertical shafts journaled for rotation one in a hole in each of said beams, the said shafts being provided each with a warp engaging hook at its lower end and with a pinion at its upper end, the pinions on the several shafts intermeshing, certain of said shafts being provided with sprockets, a chain passing about the sprockets, a pivoted hand lever connected to one run of the chain, so that by vibration of the hand lever, the hooks are rotated in unison but alternate hooks in opposite directions to form the sheds, a lower cross bar provided with warp engaging hooks, and stops limiting the vibration of the hand lever to define the sheds.

2. In a rug weaving loom, a frame composed of two uprights connected at their upper ends by parallel cross beams each pro-

vided with a row of aligned holes, vertical shafts journaled for rotation one in a hole in each of said beams, the said shafts being provided each with a warp engaging hook at its lower end and with a pinion at its upper end, the pinions on the several shafts intermeshing, certain of said shafts being provided with sprockets, a chain passing about the sprockets, a pivoted hand lever connected to one run of the chain, stops limiting the movements of the hand lever, so that the hooks are rotated in unison but alternate hooks in opposite directions to form the sheds, a lower cross bar provided with warp engaging hooks, means for securing the cross bar in adjusted position upon the uprights, and means connected to the cross bar for adjusting the tension of the warps.

3. In a rug weaving loom, a frame composed of two uprights connected at their upper ends by parallel cross beams each provided with a row of aligned holes, vertical shafts journaled for rotation one in a hole in each of said beams, the said shafts being provided each with a warp engaging hook at its lower end and with a pinion at its upper end, the pinions on the several shafts intermeshing, certain of said shafts being provided with sprockets, a chain passing about the sprockets, a pivoted hand lever connected to one run of the chain, stops limiting the movements of the hand lever, so that the hooks are rotated in unison but alternate hooks in opposite directions to form the sheds, a lower cross bar provided with warp engaging hooks, means for securing the cross bar in adjusted position upon the uprights, a treadle connected to the cross bar for lowering the same, and counter-weights acting to raise the same.

In testimony whereof, I have signed my name at Milwaukee, this 1st day of May, 1926.

JOSEPH F. PTACEK.
